UNITED STATES PATENT OFFICE

LOUIS A. CORNELIUS, OF GRAND RAPIDS, MICHIGAN, ASSIGNOR TO WOLVERINE BRASS WORKS, OF GRAND RAPIDS, MICHIGAN, A CORPORATION OF MICHIGAN

WRENCH

Application filed November 28, 1930. Serial No. 498,649.

The present invention relates to wrenches, particularly such as have spaced jaws gripping the work therebetween; and its object is to provide an improved wrench of that character having a handle carrying the jaws turnably thereon to positions wherein the wrenching operation may be effected by the lateral movement of the handle or by its rotative movement about its longitudinal axis; and further, to provide in such a wrench improved means for releasably holding said jaws in turned position.

This and any other and more specific objects hereinafter appearing are attained by, and the invention finds preferable embodiment in, the illustrative wrench structure particularly described in the body of this specification and illustrated by the accompanying drawings, in which:

Figure 1 is a side view of a wrench showing in solid lines its jaws turned on the handle to one operative position, and showing in dotted lines the said jaws turned to another operative position;

Figure 2 is a side view of the same, turned a quarter way around about the handle's longitudinal axis;

Figure 3 is a left-hand end view of the same (i. e. the end of the wrench carrying the jaws), the handle being shown in transverse section taken on line 3-3 of Figure 2;

Figure 4 is a fragmentary view of said end of the wrench, the jaws being turned on the handle to a position intermediate operative positions;

Figure 5 is a side view of parts of the wrench showing a modified construction;

Figure 6 is a sectional view of said parts taken on line 6-6 of Figure 5; and

Figure 7 is a side view of parts of a wrench showing another modified construction.

In these drawings is illustrated a wrench having an elongated handle 1 provided with a rotary bearing 2 whose axis extends transversely to the longitudinal axis of the handle.

A pair of cooperating wrench jaws 3, 4 are carried by this handle and are turnable together relatively thereto, the inner jaw 3 having a spindle portion 5 rotatable in said bearing 2. The outer jaw 4 is mounted on

the inner jaw 3 swingably about an axis transverse to the axis of bearing 2; the jaws being pivotally connected by a pintle 6 passing through the ears 7 and 8 of jaws 3 and 4 respectively.

The handle's bearing 2 is provided with angularly spaced keeper recesses 9 having inclined opposite sides 10 as seen in Figures 5 and 6; or (and preferably) with recesses 9¹ whose opposite sides are respectively inclined as shown at 10¹ and abrupt as shown at 10² in the other views, wherein these recesses 9¹ form essentially ratchet teeth. The inner jaw 3 has a detent in form a radial rod 11 extending through its spindle portion 5 and engaging in the recesses 9 to yieldingly hold the jaws against turning in the bearing 2; or in the recesses 9¹ to hold the jaws from turning in one direction and permit their turning movement in the opposite direction.

A coiled spring 12 surrounding this spindle portion and pressing between its disk collar 13 and a shoulder 14 of the handle yieldingly urges the detent into engagement in the recesses. The jaws 3, 4 have curved adjacent surfaces 15, 16 respectively provided as shown with serrations and cooperating to grip between them the work piece, as a circular rod or pipe indicated in dotted lines at 17, 17¹.

One pair of opposite recesses 9 or 9¹ are disposed parallelly with the handle's longitudinal axis, another pair being disposed at right angles to said axis. Thus the jaws may be turned to the position shown in Figures 2 and 3 and in solid lines in Figure 1 to grip a pipe 17 extending at right angles to the handle's axis, whereupon the handle is moved laterally in a plane at right angles to the pipe's axis to wrench the same; or the jaws may be turned to a position at right angles to the handle's axis as shown in dotted lines in Figure 1 to grip a pipe 17¹ extending parallelly with the handle, whereupon the handle is rotated about its axis in the wrenching operation.

A cross bar handle portion 18 is shown slideable in a bearing 19 of the handle 1. In the modified construction shown in Figure 7 the jaws 3¹, 4¹ are not connected swingably rela-

tively to each other but are angularly spaced apart, the work (as the pipe 17) being wedgely held between them. The inner jaw has a spindle portion, and a detent, and the handle has a rotary bearing with recesses in which the detent engages—all as shown in the other views.

The invention being intended to be pointed out in the claims, is not to be limited to or by details of construction of particular embodiments thereof illustrated by the drawings or hereinbefore described.

I claim:

1. A wrench comprising a handle, cooperating jaws disposed wholly at one side of the handle parallel therewith and pivoted thereto to face forwardly, rearwardly or laterally, and holding means for securing the jaws in the desired adjusted position.
2. A wrench comprising a handle, cooperating jaws disposed wholly at one side of the handle parallel therewith and pivoted thereto to face forwardly, rearwardly or laterally, and a ratchet connection between the jaws and handle.
3. A wrench comprising a handle, a jaw at one side of the handle parallel therewith and pivoted thereto to turn about an axis perpendicular to the handle into positions facing forwardly or rearwardly or laterally, a co-acting jaw carried by the pivoted jaw, and holding means between the pivoted jaw and handle to maintain them in the desired position.
4. A wrench comprising a handle having a transverse bearing and recesses at the sides of the bearing, a jaw parallel with and disposed at one side of the handle and provided with a spindle mounted in the said bearing and having a detent to engage the said recesses, a spring holding the detent in the recesses, and a second jaw pivoted to the first mentioned jaw.

In testimony whereof I have hereunto set my hand at Grand Rapids, Michigan, this 24th day of November, 1930.

LOUIS A. CORNELIUS.
